3 Claims. (Cl. 235—61.7)

1

The present invention relates to apparatus for comparing perforated record data and which is designed for use in connection with accounting machines for merging groups of tabulating cards, as for example, the record controlled machine shown and described in the U. S. patent to R. E. Page, No. 2,359,670, dated October 3, 1944. In this patent two comparing units, called in the patent "primary and secondary comparing units," are found. The construction of these units is such that they each constitute an analyzing mechanism capable of comparing between them the numbers represented by perforations in the tabulating cards. Generally speaking, these comparing units are capable of detecting an equal, a high or a low condition between the two numbers represented on the cards.

In a co-pending application of I. Ghertman, Serial No. 466,834, filed November 13, 1942, under the provisions of Commissioner's Order No. 3662, for "Record comparing devices," and which application has been allowed but on which action has been suspended for lack of legislation permitting valid dating of the application, and now abandoned, another type of comparing unit is disclosed. This latter type of unit is suitable for use in the machine of the first mentioned patent and by means thereof alphabetic indications may be compared by a determination of whether a letter or group of letters, as for example a word, is to be placed in alphabetic order before, after or with another letter, group of letters or a word. In the numerical comparing unit of the original record controlling machine, exemplified by the above mentioned Page patent, and in the alphabetic comparing unit of the improvement as exemplified in the above mentioned application, as well as in all such comparing units of this general type, the comparing apparatus depends largely for its operation upon mechanical instrumentalities which, although they may, in the final analysis, be employed to actuate electrical devices including various circuit making and breaking mechanism, are nevertheless mechanical in their function and, as such, consisting as they do of complicated ratchet mechanisms, including toothed sectors, pawls, linkages and the like, are relatively delicate and, furthermore, are costly inasmuch as they require detailed machining operation in their manufacture.

The present invention is designed as an improvement over all such electromechanical comparing devices as those outlined above in that in practice thereof the mechanical details are reduced to a minimum and the apparatus func-

tions rather as an electrical device than as a mechanical one. Moreover, the nature of the electrical control circuits and instrumentalities employed in the present invention is such that the apparatus is capable of simultaneously effecting alphabetical comparisons at will and, consequently, of effecting either alphabetic or numeric comparisons exclusively.

According to the present invention, the analyzing circuits of an accounting machine of the type set forth in the above mentioned Page patent are so modified and augmented by the provision of electrical instrumentalities that a process is followed wherein the significant figures of the same digital order of a multi-digit number may be compared by the use of three contact parts or elements electrically isolated from one another and cooperating with the analyzing devices in such a way that each of these three parts respectively control electrical circuits corresponding to an equal, a high or a low condition. In carrying out this principle, as in the case of the mechanical devices previously described, use of primary and secondary comparison units is resorted to for both zone and digital comparisons.

In order to facilitate a comprehension of the invention, a description will be given as an indication and not as a limitation of one embodiment of the invention arranged to be manually controlled and it will be understood that the manipulation thereof is performed according to a conventional codification in which a given number is represented by a single perforation in a selected column of a card at one of the numerical or digital index positions "1" to "9" thereof. According to this codification, a given letter is represented by two perforations located in the same column of a card, one of these perforations corresponding to one of the numerical or digital index positions "1" to "9" inclusive, while the other perforation is a so-called "top" or "zone" perforation, i. e., a perforation corresponding to one of the index positions "0", "11" and "12".

In the actual practice of the invention wherein the comparing apparatus is associated with an accounting machine, it will be understood that the various units will be mounted in a suitable manner on the shafts of corresponding actuators in the accounting machine with which the units are associated. In order that these actuators may set up the respective characters which are to be compared in any instance, the units are composed of primary comparing distributors and secondary comparing distributors, the analyzing devices of the latter being suitably connected to

the jacks of the former. The primary comparing distributors each include a primary zone distributor and a primary digit distributor, while the secondary comparing distributors each include a secondary zone distributor and a secondary digit distributor.

The principle involved in the present invention resides in an arrangement of the above mentioned comparing elements for each digital order of magnitude of both alphabetic and numeric indications to be compared wherein a group of zone comparing elements and a group of digit comparing elements are connected to each other electrically by a suitable multiple wire or cable. In other words, the invention contemplates a new combination of groups of primary and secondary elements with other groups of primary and secondary elements, one group of elements being designed for digital comparison and positioning according to the passage of punched holes "9" to "0" inclusive under the analyzing brushes of an accounting machine, whereas the other group of elements is designed for zone comparison and positioning according to the passage of punched "top" or zone holes "0", "11" and "12" through an accounting machine.

In the form of the invention shown, the secondary zone comparing elements are in the form of rotors formed of insulating material carrying on their peripheries two opposed conducting segments between which there are disposed two tooth-shaped extensions or segments formed on a conducting ring electrically insulated from the two segments. A cooperating stator carries analyzing brushes connected to the jacks 0, 11, 12 and 13 of an associated primary zone distributor.

The secondary digit comparing elements are similarly constructed and the stator thereof carries analyzing brushes connected to the jacks "9" to "0" inclusive of an associated primary digit distributor. The stators of both secondary distributors are provided with additional analyzing brushes, hereinafter referred to as status selecting brushes, which are respectively connected to output or work circuits corresponding to the equal, high or low states.

In order that the invention may be better understood, there will be a description by way of indication, and not of limitation, of one mode of realization of the invention involving the comparison of two combined alphabetic and numeric indications which are taken as examples. The two indications selected for example are arbitrarily chosen as "C7M" and "C7E" and, accordingly, in the various disclosures of the accompanying drawings, the various electrical instrumentalities have been set up to illustrate a comparison between these indications.

In these drawings:

Fig. 1 is a perspective view, entirely schematic in its representation, of a group of zone comparing instrumentalities including a primary zone distributor and a secondary zone distributor, together with manual means for controlling these distributors.

Fig. 2 is a schematic view, similar to Fig. 1, showing a primary digit distributor and a secondary digit distributor, together with control means therefor.

Fig. 3 is a wiring diagram of an assembled alphabetic and numeric comparing unit capable of accommodating three numeric or alphabetic orders of magnitude.

Fig. 4 is a schematic view in table form showing the particular codification system employed.

Referring now to Fig. 4, the apparatus is designed to represent a conventional codification system in which a predetermined letter is represented by two punched holes situated in the same column of a card and in which a predetermined number is represented by a single punched hole in a card column. Thus, for example, the letter "C" will appear in the form of two punched holes in a particular card column, one hole being formed in the "3" digit zone or index point position and the other hole being formed as a "top" or "zone" perforation in the "12" index point position or zone, while the numeral "7" will appear on the card as a single hole punched in the "7" digit or index point position of the card. It is obvious that any other codification system could be adopted without departing from the spirit of the invention.

In machines of the type shown and described in the above mentioned Page patent, all numeric indication, i. e., those corresponding to the index point positions "9" to "0," are registered by actuating devices designated as numeric, whereas all alphabetic designations, i. e., those utilizing a "top" hole corresponding to the index point positions 0, 11 and 12 are registered by actuating devices referred to as alphabetic. These alphabetic and numeric devices are essentially the same in principle, but while the electrical circuits of the numeric devices permit registration only during passage of punched holes "9" to "0," the circuits of the alphabetic devices permit registration only at the passage of the so-called "top" or "zone" holes "0," "11" and "12". These latter devices, namely, the alphabetic devices, will automatically become engaged at a cycle point corresponding to a reading of the punched hole "0" and will become disengaged at a point in the cycle corresponding to the reading of the zone hole which presents itself under the analyzing brushes of the accounting machine.

In a case where no zone hole exists in the card, i. e., when there exists in the column undergoing sensing only a single punched hole representative of a numeral, the alphabetic devices go beyond the point 12 in the cycle and are disengaged at the point 13.

In the present embodiment of the invention, as illustrated herein, the zone actuating devices are designated in Fig. 1 at 10 and 20 respectively, the former being hereinafter referred to as a primary zone actuating device and the latter being referred to as a secondary zone actuating device. The primary zone actuating device 10 is adapted to be manually or otherwise brought to a position representative of the zone in the primary card associated with a particular letter which, in the example selected, is the letter "C", this being the letter in the highest order of the indication C7M selected for comparison with the indication C7E. The secondary zone actuating device 20 is also adapted to be manually or otherwise brought to a position representative of the zone in the secondary card associated with the letter in the corresponding highest order of the indication undergoing comparison which, in the present instance, is also the letter "C." Thus, in both instances, the primary and secondary devices 10 and 20 are brought to a "12" position as may be determined from the codification system illustrated in Fig. 4.

The digit actuating devices are designated in Fig. 2 at 30 and 40 respectively, the former being referred to hereinafter as a primary digit actuating device and the latter as a secondary digit

actuating device. The primary digit actuating device 30 is adapted to be manually or otherwise brought to a position representative of a numerical or digit hole in the primary card associated with the letter of the highest order, namely, the letter "C." The particular index position associated with the letter "C," as determined from the codification table of Fig. 4, is the "3" position. The secondary digit actuating device 40 is adapted to be manually or otherwise brought to a position representative of the digit index position associated with the letter "C" in the corresponding highest order of the indication of the secondary card undergoing comparison which, in the present instance, is also the index position "3." Thus, for the indication selected for comparison, the devices 30 and 40 are both brought to a "3" position.

The primary and secondary digit actuating devices 30 and 40 also become operative where numerical comparisons are concerned, as will become apparent presently. In such an instance, no zone hole will appear in such columns as carry numerical designations and the primary zone and secondary zone actuators will then be brought to the "13" position and disengaged.

Referring now to Fig. 1, the secondary zone distributor is schematically shown and is designated in its entirety at 50 and includes a rotor 14. In the schematic showing, the rotor includes a body portion 16 of suitable insulating material, such as Bakelite, on the circumference of which there is disposed a pair of conducting segments 18 and 22 which are opposed to each other on the rotor and which are so situated as to include therebetween insulated spaces 24 in which there project a pair of extensions 26 and 28 which are generally of tooth-shaped configuration and which are integrally formed on a conducting ring 32. The conducting ring 32 and two segments 18 and 22 are electrically isolated from one another.

The secondary zone distributor 50 also includes a stator, the details of which are lacking in the schematic showing of Fig. 1 but which include a series of analyzing brushes 34 designed for co-operation with the three contact elements 18, 22 and 32 of the rotor 14. The brushes, in addition to their designation at 34, have also been labeled with numbers corresponding to their numerical functions in the comparing device. These labeling numbers may be distinguished from reference character numbers by the absence of lead lines. The secondary zone distributor includes only four comparing brushes 34 labeled 0, 11, 12 and 13 and they correspond to the four zones 0, 11, 12 and 13.

Three additional circuit selecting brushes 36, labeled L, E and H, are associated with the stator and these latter brushes respectively control circuits representing a low condition, an equal condition and a high condition, as previously explained. The nature of the specific circuits which operate under the control of these brushes will be set forth when a description of Fig. 3 is undertaken. The brush L is on a level with the brush 0; the brush H is on a level with the brush 13, and these two latter brushes are situated in a plane offset from and parallel to the plane of the brushes 0, 11, 12 and 13. The brush E cooperates electrically with the conducting ring 32 and is situated in the stator accordingly.

Referring now to Fig. 2, the secondary digit distributor is designated in its entirety at 60 and is similar in its general organization to the secondary zone distributor 50. The distributor includes a rotor and a stator, analyzing brushes,

circuit selecting brushes, etc., all of which have been designated on the drawings with reference numerals that correspond to those of Fig. 1 with a distinguishing prime mark. Whereas the secondary zone distributors are provided with four analyzing brushes 0, 11, 12 and 13 and three circuit selecting brushes L, E and H, the secondary digit distributor includes ten analyzing brushes 34' labeled 0 to 9 inclusive and three circuit selecting brushes 36' labeled L, E and H, as in the case of the secondary zone distributor, and representing a low condition, an equal condition, and a high condition respectively.

The secondary zone distributor rotor 14 is mounted upon a shaft 38 in common with the secondary zone actuator 20 and the secondary digit distributor 60 is mounted on a shaft 42 in common with the secondary digit actuator 40.

The secondary zone distributor 50 is associated with a primary zone distributor 70 and the secondary digit distributor 60 is associated with a primary digit distributor 80 (see Fig. 3 wherein all of these distributors are diagrammatically illustrated in position in the labyrinth circuits which they control).

Referring again to Fig. 1, the primary zone distributor includes four contact jacks 45 labeled 0, 11, 12 and 13, which are connected to the respective brushes 34 labeled 0, 11, 12 and 13 of the secondary zone distributor by circuit wires a, b, c and d. The primary zone distributor also includes a segment 44 which is electrically connected by a circuit wire e to a source of current S. The primary zone distributor 70 is provided with a dual brush arrangement 46 mounted on a shaft 48 in common with the rotor of the primary zone actuator 10.

It will be remembered that the structure of the present invention has been illustrated in connection with a specific problem or example wherein the composite character arrangement "C7M" on a card is to be compared with the character arrangement "C7E" on a secondary card. During comparison of these two character groups, comparison of the first or highest order characters in the groups, which in the present example is the letter "C," necessitates engagement of the dual brush 46 with the jack 45 labeled 12. This may be attained by a manual or automatic setting of the primary zone actuator 10. The secondary zone actuator 20 will also be manually or automatically set into the "12" position and in such an instance the toothed extension 26 will fall under the analyzing brush 34 labeled 12.

Referring now to Fig. 2, the secondary digit distributor 60 is associated with the primary digit distributor 80 in the same manner in which the two distributors 50 and 70 are associated. In the case of the primary digit distributor, the jacks, dual brush and other elements corresponding to the elements of the primary zone distributor have been given similar reference characters with the application of a prime mark thereto. The dual brush 46' is mounted upon a shaft 52 associated with the primary digit actuator 30. The jacks 45' of the primary digit distributor 80 are ten in number and are connected by circuit wires f to o inclusive. The segment 44' is connected by a wire p to the brush E of the secondary zone distributor 50 (see also Fig. 3). Returning now to the problem under consideration wherein the group "C7E" is to be compared with the group "C7M" on primary and secondary cards respectively, the table of Fig. 4 indicates that for comparison of the two letters "C" in the corresponding highest digital

orders of the groups, the primary digit actuator and the secondary digit actuator 30 and 40 respectively will each be set, either manually or otherwise, to an indication "3", which is the digital part of the codification and augments the zone part 12. This will allow the brush 46' to fall on the jack 3 and the toothed extension 26' to underlie the analyzing brush 3.

Referring now to Fig. 3, when the electrical diagram for the comparing apparatus is set up to accommodate comparison of the character group "C7E" on the primary card with the character group "C7M" on the secondary card, this figure is divided into three sections or zones labeled H, T and U, reading from left to right, and representative of the highest order of comparison, intermediate order of comparison and lowest order of comparison and which, were the designations purely numerical instead of mixed numerical and alphabetical, would represent units, tens and hundreds orders.

The schematic set-up of structure in Figs. 1 and 2 is designed to represent the left zone H of Fig. 3 and it will be understood that the middle and right-hand zone of Fig. 3 may well be accommodated by manipulation, either manual or automatic, of the actuators 10, 20, 30 and 40.

The diagram of Fig. 3 may be represented by the following table:

Character Data	H	T	U
Primary Character Group C7E.	C Primary (Zone).....12 Primary (Digit).... 3	7 Primary (Zone).....13 Primary (Digit).... 7	E Primary (Zone).....12 Primary (Digit).... 5
Secondary Character Group C7M.	C Secondary (Zone)....12 Secondary (Digit).... 3	7 Secondary (Zone)....13 Secondary (Digit).... 7	M Secondary (Zone)....11 Secondary (Digit).... 4

In the operation of the apparatus, the comparison is first effected by comparing the two corresponding left-hand highest order significant letters or figures of the indications (namely, "C7E" and "C7M") to be compared. If an equal condition is detected (as is the case in the present example), the comparison is automatically directed to the following significant letters or figures of the next lowest or intermediate order. If an equal condition is again detected (as is the case in the present instance), the comparison is again directed to the significant letters or figures of the next lower order. Where character groups of many orders are undergoing comparison, the above arrangement continues until a high or a low condition is detected, after which no further comparisons of lower orders are necessary.

Where automatic operation is concerned in connection with machines of the type set forth in the patent disclosures mentioned earlier in this specification, at a chosen cycle point a cam controlled contact or other circuit controlling device, herein represented simply by a manual switch SW, is operated and current flows from the source S through wire e, segment 44 of the primary zone distributor, brush 46, "12" jack 45, "12" wire c, "12" brush 34 of the secondary zone distributor, toothed extension 26, ring 32, "E" brush 36, wire p, contact segment 44' of the primary digit distributor, brush 46', "3" jack 45', "3" wire i, "3" brush 34', toothed extension 26', ring 32', "E" brush 36', and through a wire q in the circuit which represents an equal condition and leading to the next comparison stage for the two numerical characters "7" in the character group selected for comparison.

In this second comparative stage, the circuit continues from the wire q to the segment 44 of

the primary zone distributor, brush 46, "13" jack, wire d, "13" brush of the secondary zone distributor, toothed extension 26, "E" brush, wire p, ring 44' of the primary digit distributor, brush 46', "7" jack, wire m, "7" brush, toothed extension 26', ring 32', "E" brush, and a wire r in an equality representing circuit leading to the next stage.

In the two stages through which circuits have just been traced, conditions of equality, first, between the alphabetic character C and, second, between the numerical character 7, have existed. In the stage to follow, an unequal condition will be found since a comparison between the characters E and M is to be made. As will appear presently, this inequality indicates that the primary letter E is lower than the secondary letter M, or, conversely, that the secondary letter M is higher than the primary letter E, and thus a suitable output circuit will be accordingly energized.

This output circuit is designated as "S>P" and indicates that the card bearing the primary designation is to be placed before the card bearing the secondary designation. The primary zone actuator 10 and the secondary zone actuator 20 are accordingly manually or otherwise preset, the former for a 12 indication and the latter for an 11 designation, which are the zone designations for the characters E and M respectively. Similarly,

the primary digit actuator 30 and the secondary digit actuator 40 are preset for indications 5 and 4 respectively which are the digit index positions for the two designations. Then, from the wire r, the circuit continues to the segment 44 of the primary zone distributor, brush 46, 12 jack, wire c to the "12" brush, which now instead of resting on the toothed extension 26 rests upon the segment 18. This may be determined from an inspection of Fig. 1 for, when it is realized that the secondary zone actuator 20 is set so that the 11 brush rests upon the toothed extension 26, the 12 brush will then rest upon the segment 18. From the segment 18 the circuit continues through the circuit selecting brush H, wires s and t to the output circuit "S>P."

From the description it will be seen that an inequality has been detected at the point where a comparison of the zone positions of the letters E and M appearing on the primary and secondary cards respectively is made. At this point, the previously traced labyrinth circuit leading all the way from the source through the primary zone distributor and secondary zone distributor in the two highest orders of the characters under consideration is diverted directly to the inequality circuit "S>P" and does not pass through the primary and secondary digit distributors of the lowest order of the characters under consideration. It is also clear that had the inequality been reversed so that the primary character was greater than the secondary character, the circuit would have led out from the secondary zone distributor through the brush L and from thence directly to the output circuit "S<P." Likewise, had the comparison resulted in an equality of characters, a labyrinth circuit would be traced through the primary and secondary zone distributors, and pri-

mary and secondary digit distributors to the conducting ring 32' in the third or lowest order of the comparison to the output circuit "S=P."

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. Apparatus for comparing the relative magnitude of a primary quantity with the magnitude of a secondary quantity to determine whether a low, an equal or a high condition exists in the comparison comprising a primary distributor and a secondary distributor, each of said distributors including a movable part and a stationary part, the stationary part of said primary distributor including a series of contact elements representing progressively increasing digit values and the movable part thereof including a settable distributor brush designed for selective engagement with said contact elements, means for supplying energizing current to said brush, the stationary part of said secondary distributor including a series of contact brushes representing digit values corresponding to the values represented by said contact elements, means electrically connecting each contact element to a respective contact brush, the movable part of said secondary distributor including three settable contact segments which are electrically insulated and fixed relative to one another, one representing a low condition, one representing an equal condition and the other representing a high condition in the comparison and designed for cooperation with said contact brushes, a plurality of output circuits leading from said secondary distributor representative of a low, an equal and a high condition respectively, of a contact brush for each circuit, said last mentioned contact brushes being positioned so that when said distributor brush is set in accordance with the magnitude of said primary quantity and the movable part of said secondary distributor is set according to the magnitude of said secondary quantity energizing current will flow from said distributor brush to one of said output circuits, depending upon the existence of a low, an equal or a high condition between the primary and secondary quantities.

2. Apparatus for comparing the relative magnitude of a primary quantity with the magnitude of a secondary quantity to determine whether a low, an equal or a high condition exists in the comparison comprising a primary distributor and a secondary distributor, each of said distributors including a rotary part and a stationary part, the stationary part of said primary distributor including a series of contact elements representing progressively increasing values and the rotary part thereof including a settable distributor brush designed for selective engagement with said contact elements, means for supplying energizing current to said brush, the stationary part of said secondary distributor including a series of contact brushes representing values corresponding to those represented by said contact elements, means electrically connecting each contact element to a respective and corresponding contact brush, the rotary part of said secondary distributor including three settable contact segments,

one representing a low condition, one representing an equal condition and the other representing a high condition in the comparison and designed for cooperation with said contact brushes, a plurality of output circuits leading from said secondary distributor representative of a low, an equal and a high condition respectively, a contact brush for each circuit, said last mentioned contact brushes being positioned so that when said distributor brush is set in accordance with the magnitude of said primary quantity and the rotary part of said secondary distributor is set in accordance with the magnitude of said secondary quantity energizing current will flow from said distributor brush to one of said output circuits, depending upon the existence of a low, an equal or a high condition between the primary and secondary quantities.

3. Apparatus for comparing the relative magnitude of a primary quantity with the magnitude of a secondary quantity to determine whether a low, an equal or a high condition exists in the comparison, said quantities being represented by code perforations in respective record media undergoing comparison including zone perforations and digit perforations, said apparatus comprising a primary zone distributor and a secondary zone distributor, each of said distributors including a rotary part and a stationary part, the stationary part of said primary zone distributor including a series of contact elements representing different zone perforations in the record media and the rotary part thereof including settable distributor brushes designed for selective engagement with said contact elements, means for supplying energizing current to said brush, the stationary part of said secondary distributor including a series of contact brushes representing the zone perforations corresponding to those represented by said contact elements, means for supplying energizing current to said brush, the stationary part of said secondary distributor including a series of contact brushes representing the zone perforations corresponding to those represented by said contact elements, means electrically connecting each contact element to a respective and corresponding contact brush, the rotary part of said secondary distributor including three contact segments, one representing a low condition, one representing an equal condition and the other representing a high condition in the comparison of zone perforations and designed for cooperation with said contact brushes, a plurality of output circuits leading from said secondary distributor representative of a low, an equal and a high condition respectively, a contact brush for each circuit, said last mentioned contact brushes being positioned so that when said distributor brush is set in accordance with a zone perforation representative of the primary quantity and the rotary part of said secondary distributor is set according to the zone position representative of the secondary quantity, energizing current will flow from said distributor brush to one of said output circuits, depending upon the existence of a low, an equal or a high condition between the zone perforations which are representative of the primary and secondary quantities, a primary digit distributor and a secondary digit distributor each including a rotary part and a stationary part, the stationary part of said latter distributor including a series of contact elements each representative of a digit and the rotary part thereof including a settable distributor brush designed for selective engagement with said latter contact elements, means electrically connecting said latter distributor brush in the output circuit leading from said secondary zone distributor, the stationary part of said secondary digit distributor including a series of contact brushes representing digit values

11

corresponding to those represented by said latter contact elements, means electrically connecting each contact element of the primary digit distributor to a respective and corresponding contact brush of the secondary digit distributor, the rotary part of said secondary digit distributor including three settable contact segments, one representing a low condition, one representing an equal condition, and the other representing a high condition in the comparison of digit perforations in the record media undergoing comparison and designed for cooperation with the contact brushes of said secondary digit distributor, a plurality of output circuits leading from said secondary digit distributor representative of a low, an equal and a high condition respectively in the comparison of digit perforations in the record media, a contact brush for each of said

10 15

12

latter circuits, said last mentioned contact brushes being positioned so that when the distributor brush of said primary digit distributor is set in accordance with the digit perforation of said primary quantity and the rotary part of said secondary digit distributor is set in accordance with the magnitude of the digit portion of said secondary quantity, energizing current will flow from the distributor brush of said primary digit distributor to one of said latter output circuits, depending upon the existence of a low, an equal or a high condition between the digit perforations which are representative of said primary and secondary quantities.
